UNITED STATES PATENT OFFICE.

HENRY B. PATCH, OF KANSAS CITY, MISSOURI, ASSIGNOR TO GENESY ELECTRIC
LANTERN COMPANY, OF RAWLINS, WYOMING, A CORPORATION OF WYOMING.

LANTERN.

Application filed April 16, 1926. Serial No. 102,445.

My invention relates to improvements in lanterns. It relates particularly to lanterns of the type having a casing adapted to contain a battery for operating an electric lamp.

5 One of the objects of my invention is to provide a lantern of the kind described with a novel handle mechanism arranged to permit a handle to be moved to and held in either a raised operative position or lowered

10 to a compact position.

A further object of my invention is to provide novel yielding means for retaining the handle in the elevated position.

15 A further object of my invention is to provide a handle mechanism of the kind described, which is simple, cheap to make, durable, strong, not liable to get out of order, and which is easy to operate.

20 The novel features of my invention are hereinafter fully described and claimed.

In the accompanying drawing, which illustrates the preferred embodiment of my invention,

25 Fig. 1 is a side elevation of a lantern provided with my improvement.

Fig. 2 is another side elevation of the same, partly broken away.

Fig. 3 is a top view of the same.

30 Fig. 4 is a section on the line 4—4 of Fig. 2.

Fig. 5 is a section on the line 5—5 of Fig. 2.

Similar reference characters designate similar parts in the different views.

35 1 designates the cylindrical hollow body of a lantern casing adapted to contain a battery, not shown, and provided at diametrically opposite sides respectively with two ears 2, which at their upper ends are respectively

40 provided with two vertical tubular guiding portions 3 in which are respectively slidably fitted the two arms 4 of an inverted U shaped handle 5. The lower ends of said arms 4 are respectively screw threaded and have fitted thereon two nuts 6, which form heads

45 adapted to be respectively engaged at their lower ends by two springs 7, which may be two flat resilient plates respectively fastened by rivets 8 to raised portions 9, with which

50 the ears 2 are respectively provided. The upper ends of said springs 7 are respectively provided with two V shaped portions 10,

which respectively bear against the inner sides of the arms 4 of the handle, and which, when the handle 5 is pulled from the lowermost position, shown in dotted lines in Fig. 1, to the uppermost position, shown in solid lines in Figs. 1 and 2, respectively engage the lower ends of the nuts 6, thereby releasably holding the arms in their uppermost positions.

When the lantern is not to be used, the handle 5 is forced downwardly to the lowermost position, shown in dotted lines in Fig. 1, the friction exerted by the springs 7 ⁶⁵ against the arms preventing the latter from accidentally moving to the operative position in case the lantern is overturned.

The nuts 6, striking against the lower ends of the tubular portions 3, limit the upward ⁷⁰ movement of the arms 4.

I do not limit my invention to the structure shown and described, as modifications, within the scope of the appended claims, may be made without departing from the spirit ⁷⁵ of my invention.

What I claim is:—

1. In a lantern, a casing having two ears provided respectively with vertical tubular portions, an inverted U shaped handle the arms of which are vertically slidable in said tubular portions, and springs fastened to said ears and slidably engaging said arms, and arranged to releasably hold said arms in their uppermost positions.

2. In a lantern, a casing having two diametrically opposite ears provided respectively with vertical tubular portions, an inverted U shaped handle the lower ends of the arms of which are provided with heads, said arms being vertically slidable in said tubular portions, and springs secured to said ears and disposed in the path of and bearing against said arms, said heads in their uppermost positions engaging the lower ends of said tubular portions, and in said positions being engaged and held in their uppermost positions by said springs.

3. In a lantern, a casing having two diametrically opposite ears the upper end of each of which is formed into a vertical cylinder, and each ear below said cylinder having a raised portion, an inverted U shaped handle having its two arms respectively slidably fit-

ted in said cylinders, the lower ends of said arms being threaded and having fitted thereon two nuts of greater diameter than said arms and adapted to strike against the lower ends of said cylinders to limit the upward movement of said arms, and springs fastened to said raised portions of said ears and bear-

ing against said arms and adapted to engage the lower ends of said nuts to hold said arms from moving downwardly from their uppermost positions. 10

In testimony whereof I have signed my name to this specification.

HENRY B. PATCH.
